UNITED STATES PATENT OFFICE.

FRANK J. SENG, OF CHICAGO, ILLINOIS, ASSIGNOR TO THE SENG COMPANY,
OF SAME PLACE.

DESIGN FOR A CLUTCH MEMBER.

SPECIFICATION forming part of Design No. 31,190, dated July 11, 1899.

Application filed June 3, 1899. Serial No. 719,314. Term of patent 3½ years.

To all whom it may concern:

Be it known that I, FRANK J. SENG, a citizen of the United States, residing at Chicago, in the county of Cook and State of Illinois, have invented a novel Design for a Clutch Member; and I do hereby declare the following to be a full, clear, and exact description of the invention.

My invention relates to a novel design for a clutch member, the object being to provide a device of this character of neat and ornamental appearance.

In the accompanying drawings, illustrating my design, Figure 1 is a perspective view of the clutch member. Fig. 2 is a plan view of same. Fig. 3 is an end elevation of same. Fig. 4 is a sectional view of same on the line 4-4 of Fig. 2.

My design consists of a base-plate A, which is narrower at its middle portion than at its ends, while the latter are rounded or partially circular and contain openings which are countersunk on one side of said plate. At its middle portion said plate A is provided with parallel flanges B, extending at angles of about ninety degrees to said plate, the corners where said plate and flanges are

joined being also rounded. Said flanges B are narrower at the points of connection with said plate than at their outer ends and are slightly rounded on their edges adjacent their points of connection with said plate A. The outermost edges of said flanges B are practically parallel with said plate along part of its length, one end being rounded or curved and forming part of a curved side edge on each side of said flanges. The other side edges of said flanges extend at angles of practically ninety degrees to the plane of the plate A and to the outermost ends of said flanges B. Said flanges also have openings adjacent the rounded side edges.

My device is very neat and ornamental in appearance.

I claim as my invention—

The design for a clutch member, substantially as shown and described.

In testimony whereof I affix my signature in presence of two witnesses.

FRANK J. SENG.
